UNITED STATES PATENT OFFICE.

FLOYD CUMMINGS, OF ONEONTA, NEW YORK.

COMBINATION TOILET SET AND CASE.

1,206,679.

Specification of Letters Patent.

Patented Nov. 28, 1916.

Application filed October 15, 1915. Serial No. 56,049.

To all whom it may concern:

Be it known that I, FLOYD CUMMINGS, a citizen of the United States, residing at Oneonta, in the county of Otsego and State of New York, have invented certain new and useful Improvements in Combination Toilet Sets and Cases; and I do hereby declare the following to be a full, clear, and exact description of the invention, such as will enable others skilled in the art to which it appertains to make and use the same.

The primary object of this invention is to combine a plurality of toilet articles, so that when not in use, they can be folded so as to occupy a minimum amount of space when placed within a suitcase or traveling bag.

Another object of the invention is to provide a device of this nature, which can be manufactured cheaply, will be durable and efficient in operation.

Other objects will appear and be better understood from that embodiment of my invention of which the following is a specification, reference being had to the accompanying drawings, forming a part thereof in which:

Figure 1 is a side view of the toilet set, showing the same in operative position. Fig. 2 is a longitudinal section taken through the casing for the toilet set when folded to inoperative position.

Referring to the drawings in detail, the numeral 1 designates a hair brush having a back portion 2, formed preferably of aluminum or similar metal, the said back having a chamber 3 therein opening into the forward end of the back portion 2. The chamber 3 removably receives a rectangular shaped mirror 4, the said mirror having the end which lies adjacent the open end of the chamber 3, provided with a rectangular shaped portion 5, which is of a greater width and length than the width and height of the chamber 3, and is adapted to close the open end of the chamber 3 when the mirror is positioned within the chamber and lies flush with the adjacent edge of the back, as shown in Figs. 1 and 2 of the drawings. The rectangular portion 5 carries a manipulating handle 6, by means of which the mirror can be conveniently withdrawn from the chamber and held in upright position. The back 2 has its rear end provided with an upwardly and outwardly extending bracket arm 6', the upper terminal

of which is provided with an apertured ear 7.

Associated with the hair brush 1, is a comb 9. This comb has a tubular back portion 10, which is substantially triangular in cross section, and has its inner side provided with comb teeth 11. The forward end of the tubular back portion of the comb, is opened, so as to admit of the insertion of a tooth brush 12 within the tubular back portion 10 when in use, the said open end being closed by a removable cap 13, which has a cylindrical extension 14 adapted to be removably received by the open end of the tubular back portion 10 of the comb.

The rear end of the tubular back portion 10 of the comb, is provided with an upwardly and outwardly extending arm 15, the upper end of which has formed thereon an apertured ear similar to the ear 7 on the bracket arm 6' and is positioned at one side of the ear 7, and a bolt 19 extends through the ears and pivotally connects the same so as to permit the comb 9 being folded over upon the brush 1, so that the teeth of the comb will be inserted within the bristles of the brush. When so folded, the toilet set is placed within a casing, designated 21, in Fig. 2, the said casing being of rectangular configuration, having one end opened and adapted to be closed by a hinged cap 22, the said cap 22 carrying a depending spring latch 23 adapted to engage over a lug 24 carried on the adjacent wall of the casing 21, so as to hold the cap 22 in closed position.

When it is desired to use the toilet articles, the same are withdrawn from the casing 21, and unfolded to the position shown in Fig. 1. If it is desired to use the comb, the brush is gripped by one hand of the operator, and the same serves as a handle for the comb, and the combing operation can be carried out in the ordinary manner. When the brush is to be employed, the tubular body 10 will serve as a handle for the brush and be grasped by the hand of the operator, so that the brush can be conveniently operated. After the combing or brushing operation, the comb is folded on the brush and the toilet set is then inserted within the case 21, as shown in Fig. 2.

From the foregoing description taken in connection with the accompanying drawings, it will be seen that I have provided a new and novel combination toilet set and case,

which when not in use, can be conveniently stored within a narrow space within a suit-case or traveling bag.

Having thus described my invention, what I claim as new is:—

As a new article of manufacture; a pair of pivotally connected elements; brush bristles carried by one of the elements; comb teeth carried by the other element; either 10 element being adapted to serve as a handle during the use of the other element; and

the said elements being adapted, when not in use, to be folded into parallelism with each other and to have the comb teeth engage in the brush bristles.

15

In testimony whereof I affix my signature in presence of two witnesses.

FLOYD CUMMINGS.
